CLAIM

(21) Appl. No.: **29/436,478**

The ornamental design for a removable face pack for an electronic landscape lighting controller, as illustrated and described.

(22) Filed: **Nov. 6, 2012**

DESCRIPTION

(51) **LOC (9) Cl.** 13-03

FIG. 1 is an isometric view of the face pack taken from the front side thereof;

(52) **U.S. Cl.**

FIG. 2 is an isometric view of the face pack taken from the rear side thereof;

USPC **D13/162**

FIG. 3 is a front elevation view of the face pack;

(58) **Field of Classification Search**

FIG. 4 is an end elevation view of the face pack taken from the right side of FIG. 3;

USPC D13/162, 164; D10/46, 49, 96;
137/624.11; 239/69; 315/152, 158;
361/622, 627, 628, 643; 700/284

FIG. 5 is an end elevation view of the pack panel taken from the left side of FIG. 3;

See application file for complete search history.

FIG. 6 is a top elevation view of the face pack taken from the top of FIG. 3;

(56) **References Cited**

FIG. 7, is a bottom elevation view of the face pack taken from the bottom of FIG. 3; and,

U.S. PATENT DOCUMENTS

FIG. 8 is a rear elevation view of the face pack.
